CLAIM

The ornamental design for a portable electronic device as shown and described.

DESCRIPTION

FIG. 1 is a perspective view of a portable electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the indicated portion of the portable electronic device labeled "8" in FIG. 1;

FIG. 9 is an enlarged view of the indicated portion of the portable electronic device labeled "9" in FIG. 1;

FIG. 10 is an enlarged view of the indicated portion of the portable electronic device labeled "10" in FIG. 1;

FIG. 11 is an enlarged view of the indicated portion of the portable electronic device labeled "11" in FIG. 1;

FIG. 12 is an enlarged view of the indicated portion of the portable electronic device labeled "12" in FIG. 1;

FIG. 13 is a perspective view thereof in another position;

FIG. 14 is a perspective view thereof in another position where the screen is flipped horizontally; and,

FIG. 15 is a perspective view thereof in another position where the screen is flipped obliquely.

The even-dash broken lines illustrate portions of the electronic device that form no part of the claimed design. The shaded areas, enclosed by dot-dash broken line boundary,
